UNITED STATES PATENT OFFICE.

ALLAN HODGSON PARKER, OF ELWOOD, NEAR MELBOURNE, VICTORIA, AUSTRALIA,
ASSIGNOR TO THE BRITISH IMPERIAL OIL COMPANY, LIMITED, OF MELBOURNE,
VICTORIA, AUSTRALIA.

POURING DEVICE FOR FLUID-CONTAINERS PRINCIPALLY OIL-TINS.

1,261,431.

Specification of Letters Patent.

Patented Apr. 2, 1918.

Application filed December 26, 1917. Serial No. 208,932.

To all whom it may concern:

Be it known that I, ALLAN HODGSON PARKER, a subject of the King of Great Britain, residing at 14 Pine avenue, Elwood, 5 near Melbourne, in the State of Victoria, Commonwealth of Australia, have invented Improved Pouring Devices for Fluid-Containers Principally Oil-Tins, of which the following is a specification.

10 The present invention has been designed to provide a simple cheaply constructed device or means adapted to be readily attached by the manufacturer to metal containers, cans or tins in which oils or other liquids 15 are dispensed to the user. The device is particularly applicable for use with sheet metal oil cans or drums, and an arrangement of the device is contemplated by this invention whereby, when it is not in use, 20 it lies approximately flush with that side of the can to which it is attached, for convenience in stacking and transport of the cans; as also an arrangement whereby the 25 disadvantage of its position preventing draining of the entire contents of the can is eliminated.

A practical form of the invention is illustrated in the accompanying drawings, whereof—

30 Figure 1 is a plan, and

Fig. 2 a central vertical section of one corner of a can, showing the pouring device in out-of-use position.

Fig. 3 is a plan, and

35 Fig. 4 a central vertical section of one corner of the can showing the device in position for pouring.

Referring to the drawings, it will be seen that a practically bottomless pouring spout 40 1, which is extended or peaked on one side to form a projecting lip 2, is located about an opening preferably formed at the corner of the top of the can T and adjacent the edge, with its bottom edge concentric to said 45 opening; the said spout being formed so as to swivel or revolve as will be seen by comparing Fig. 1 with Fig. 3, or Fig. 2 with Fig. 4. For this purpose, its lower edge is provided with a projecting bead 3 50 59 adapted to engage with a correspondingly-shaped flange or socket 16 fixed to the top of the can.

When in use, the spout is rotated into a

position in which its lip projects over the corner of the can. 55

The opening in the can is closed by a suitable plug; and according to the construction shown, the socket 16 is formed with a threaded sleeve 4, which extends into the can, and a threaded plug 5 provided with a finger grip 6 is screwed into said sleeve. The top of the can at the corner where the device is attached may be inclined to provide a recess for the device and to enable the device when revolved to clear the upper flange 7 of the can. With this construction, it will be noted that when the pouring device is swung inwardly, as in Figs. 1 and 2, the top rim 8 of said device will be clear of the bottom 9 of another superposed can T¹, thus offering no difficulty in stacking or packing for transport. 65 70 75

To provide for the draining out of the small quantity of fluid which will flow into the space between one corner of the can and the sleeve 4 of the socket of the pouring device, an aperture or drain hole 10 is provided in the outer side of said sleeve and an air hole 11 is punched in the opposite side thereof. In this arrangement, the socket sleeve would be necessarily provided with a plug seal or closure device. 80

In some instances, the bottom of the sleeve 4 may be closed and required to be punctured before the contents of the can can be removed. The plug 5 is preferably sealed as an indication to a purchaser that the contents have not been tampered with; and according to one suitable arrangement, a wire 12 is threaded through a passage in the finger piece and its ends passed through a hole 13 in the spout and finally passed through a loop 14 fixed to the top of the can and the extremities of the wire connected by a seal 15. 85 90 95

What I do claim as my invention, and desire to secure by Letters Patent is—

1. A liquid-dispensing vessel, having its top provided with an opening, and with an annular socket surrounding the same, said socket being formed with a threaded sleeve which extends downward through said opening into the interior of the vessel; a practically-bottomless spout provided with a projecting pouring lip and formed at its lower edge with a bead which is rotatably engaged 100 105

with said socket to permit the spout lip to be turned into and out of pouring position; and a threaded plug removably engaged in said sleeve.

2. A liquid-dispensing vessel, having a portion of its top inclined to produce a recess, said inclined portion being provided with an opening and with an annular socket surrounding the same, and said socket being formed with a threaded sleeve which extends downward through said opening into the interior of the vessel; a practically-bottomless spout rotatably mounted over said opening and provided with a projecting pouring lip which is movable into and out of said recess during the rotation of the spout; and closure means for said opening.

said socket to permit the spout lip to be moved into and out of said recess; and a threaded plug removably engaged in said sleeve.

3. A liquid-dispensing vessel, having a 20 portion of its top inclined to produce a recess, said inclined portion being provided with an opening; a practically-bottomless spout rotatably mounted over said opening and provided with a projecting pouring lip 25 which is movable into and out of said recess during the rotation of the spout; and closure means for said opening.

ALLAN HODGSON PARKER.
